UNITED STATES PATENT OFFICE.

JOHN H. STRUVE, OF CHICAGO, ILLINOIS, ASSIGNOR TO WATER ARCH FURNACE CO., OF CHICAGO, ILLINOIS, A CORPORATION OF ILLINOIS.

SECTIONAL GRATE FOR FURNACES.

1,283,952.

Specification of Letters Patent.

Patented Nov. 5, 1918.

Application filed July 12, 1915. Serial No. 39,249.

To all whom it may concern:

Be it known that I, JOHN H. STRUVE, a citizen of the United States, and resident of Chicago, in the county of Cook and State of Illinois, have invented certain new and useful Improvements in Sectional Grates for Furnaces, of which the following is a full, clear, and exact specification.

This invention relates to improvements in sectional grates for furnaces wherein there is a gravity feed of the fuel, and for which purpose grate bars are inclined downwardly from the sides of the furnace and terminate at opposite sides of clinker bars, or else are inclined downwardly from the front of the furnace to the bridge wall with their several sections heretofore pivoted in such a manner that when shaken to remove ashes, the fresh fuel descends over upon the surface of the coked fuel thereon.

The prime object of my invention broadly stated, is to provide a sectional grate bar surface with means whereby the volatile matter and hydro-carbon gases from fresh coal fuel is conducted upwardly through the incandescent fuel, and a correspondingly perfect combustion is produced.

More specifically stated, the object of my invention is to provide a sectional grate bar surface, the location of the pivots and form of construction of which is such that when shaken the fresh fuel will descend by gravity in contact with the grate bar surface and beneath the coked fuel.

Another object of my invention is to provide a sectional grate bar surface with a connecting means adapted to not only simultaneously swing the several grate bars upon their pivotal supports, but in such a manner that the bottom bar shall have a greater range of movement than the top bar, and if need be, the several bars a differing range of movement increasing from the top to the bottom surface of the grate.

A further object of my invention is to provide a hanger for the shaft of the hand shaking lever, the construction of which is such that it may be secured in its operative position and removed when burnt out or otherwise injured, for the substitution of a new hanger without disassembling any of the several other parts of a grate structure.

With these ends in view, my invention finds embodiment in certain features of nov-

elty in the construction, combination and arrangement of parts by which the said objects and certain other objects are attained, all as hereinafter fully described with reference to the accompanying drawings, and more particularly pointed out in the claims.

In said drawings:

Figure 1 is a transverse section taken on the line 1—1 of Fig. 2 of grate bars in which my invention finds its embodiment, and which are shown in connection with a steam boiler furnace for which my invention is especially adapted.

Fig. 2 is a detail section taken on the line 2—2 of Fig. 1, and showing in elevation the grate bars at one side of the furnace.

Fig. 3 is an enlarged transverse section of one of the grate bars taken on the line 3—3 of Fig. 2.

Fig. 4 is a detail section taken on the line 4—4 of Fig. 5.

Fig. 5 is an enlarged side elevation of the grate bar frame, the hand lever and the hanger for the shaft in their operative position, with dotted lines indicating the relative position of the several grate bars when at the extreme of their upward movement.

Fig. 6 is a detail transverse section through one side of the furnace graphically illustrating the relative position of the fresh and coked fuel, with the grate bars in their normal position following the shaking down of the coked fuel, and

Fig. 7 is a similar view showing the relative position of the coked and semi-fresh fuel in their position on and relative to the grate bars at the end of their upward stroke.

Similar characters of reference indicate the same parts in the several figures of the drawings.

While I have illustrated my invention in connection with a "Dutch-oven" type of furnace in which the furnace therefor projects partly or wholly outwardly beyond the boiler 6 and the arch 7 is supported from the opposing side walls 8 and 9 of the furnace, my invention is equally well adapted for any other type of furnace in which grate bar surfaces are inclined downwardly toward each other, from the side walls of the furnace, or from the front wall toward the bridge wall thereof for the purposes of a gravity feed of the coal, and which so far

as my invention is concerned may be supplied by hand or by means of automatic stokers.

As shown in the drawing the opposing 5 side walls of the furnace are provided with seat supports for angle irons 10 and 11, toward their upper end, supports for side bars 12 and 13, the bottom ends of which rest upon lugs 14 projecting outwardly from 10 bars 15 and 16, supported at their front and rear ends (see Fig. 2) by the bridge wall 17 and the front wall 18 of the furnace.

When duplex sectional grate surfaces are employed at each side of the furnace, as 15 shown in Fig. 2, they are separated and supported at their adjacent ends respectively by additional side bars 19 and 20, and when duplex clinker bars 21 and 22 instead of a single bar are employed their opposing ends 20 are respectively supported by bars 23 and 24, projecting into the bridge wall and supported by the front wall of the furnace in the same manner before described for the bars 15 and 16.

25 The side bars 12 and 13 are respectively adjacent to the bridge wall, and the front wall of the furnace, and the side bars 19 and 20 about midway between these two points, the side bars 12 and 13 being provided toward their upper edges with elongated open slots 25, and the bars 19 and 20 with perforations at intervals of their length, for forming the bearings of pivot lugs 26 at each end of three several grate 35 bars 27, 28 and 29, constituting longitudinal members of a sectional grate surface.

The pivotal lugs 26 by means of which the several grate bars are suspended from their opposing side bars are eccentric to the axis 40 of the bars, that is to say, are located upwardly above the longitudinal center of length of the grate bars, with the result that when swung upwardly on their pivots from their normal position, the lower ends 45 of the grate bars have a substantially greater movement than their upper ends have, and whereby the bars are moved to a stepped arrangement as indicated by dotted lines in Fig. 5.

50 The grate bar sections 27, and 28 and 29 are respectively provided with downward projecting arms 30—31 and 32 preferably having cast therewith bifurcated ends, between which is confined a movable bar 33 pivoted to said arms respectively by means of pivots 34, 35 and 36, for simultaneously swinging the several sections 27, 28 and 29 on their respective pivot bearings 26.

Inasmuch, however, as shown in the drawings that the distance between pivotal supports of the grate section 27 to the pivot connecting it with the sections 33 is greater than the distance between the same points of support for the section 28, and this in 65 turn greater than the distance between the

points of the section 29, the angular distance through which these several bars swing successively increases for each bar from the top to the bottom of the grate surface.

As a means for actuating the grate sections for shaking down the grate, there is 70 removably secured by means of nut bolts 37 to the outer surface of the side bars 12 and 13 a U-shaped bracket 38 projecting in a plane below the path of movement of the 75 bar 33, and provided with an elongated slot 39 open at its upper end, the closed end of which provides a bearing for a shaft 39^a projecting outwardly beyond the front wall of the furnace, and to which is secured 80 a hand lever 40.

Shaft 39^a (see Figs. 1 and 5) has rigidly secured thereto, by means of a pin 42 passing through the shaft, a crank arm 41, the free end of which crank arm is bifurcated 85 to receive the adjacent end of a link 43 secured thereto by means of a pivot 44, the other end of which link is secured well toward the end of the bar 33 by means of a pivot 45 passing diametrically through the 90 bar 33 toward its lower end.

In operation with the lever in the position shown in Fig. 5 and at which time the surfaces of the several sections of the grate lie in the same plane, it will be seen that on 95 moving the lever 40 to the left from the position shown in Fig. 5, the bar 33 through its link connection 43 with a crank arm 41 will simultaneously move downwardly at its upper end and upwardly at its lower end, 100 indicated by dotted lines, with the result that the several sections of the grate will be swung on their pivots 26 upwardly from their normal plane, and gradually to the stepped arrangement indicated by dotted 105 lines in Fig. 5, and shift the fuel accordingly into the position graphically illustrated in Fig. 7, with the result that the entire bed of fuel resting on the grate surface is bodily lifted above its normal position thereon. 110

For a clear understanding of the operation of the devices in which my invention finds embodiment and the results attributable thereto, it should first be noted that when the coked coal is in a highly heated incandescent condition, as indicated at 46 in Fig. 6 by the lighter shading, the rough surfaces presented by coked as compared with uncoked coal produces a more or less cohesive action between the coked particles 115 and lumps, with the result that when the coke is lifted by the grate bars both when supported in contact therewith or upon the surface of an intermediate layer of uncoked coal it tends to remain in its elevated position following the receding of the grate bars therefrom.

Whereas, on the other hand there is no such cohesion between fresh coal, or that which is but slightly coked, with the re- 120 125 130

sult that when there is fresh or but slightly coked coal on the grate bars, it will from lack of cohesion of its particles descend by gravity down beneath the incandescent bed 5 of coke over the adjacent surface of the grate bars.

With the introduction of fresh fuel upon the grate bars beneath the bed of incandescent coke in a furnace provided for by 10 my invention, a number of new and useful results are produced, among which may be mentioned that of maintaining the heat of the grate bars below their burning point, from the cooling effect of the fresh fuel 15 which also provides for a freer circulation of air upwardly through the grate bars, and into the incandescent coke, but of more importance, that all of the gases released from the fresh and also incompletely coked fuel, 20 are with certainty directed upwardly through the bed of incandescent coke wherein in the highest degree of incandescence is thereby maintained for, and no doubt, producing the perfect combustion of all the 25 gases, as far as may be, rising from fresh coal and also the uncoked particles of partially coked coal.

In their operation the pivoting of the three 30 sections of the grates and their simultaneous movement indicated in the drawings, provides not only for compressing the coal from its under surface upwardly but in steps forming so to speak pockets between each section somewhat shallow at their upper end, and 35 deep at the lower edge of the grate sections, so that when the pockets are moved to their depressed position any fresh fuel thereon is free to descend by gravity from the surface of one bar to the other, and accordingly 40 make room for fresh coal feeding by gravity from its source of supply until any unoccupied space between the surface of the grate is filled.

As a means for increasing the rapidity 45 and amount of coal resting on and capable of descending the grate surface by gravity, and also of the fresh fuel from its source of supply, the increasing of the angular distance through which the several grate sections swing, beginning with the top section 50 of the grate surface, is to be regarded as an important feature of my invention.

In other words, as shown in Fig. 7, the 55 maximum depth of the incandescent fuel is directly over the lowest grate section 29, less over the section 28, and necessarily of minimum depth over the highest section 27, and which in practice requires that the bottom section 29 shall move upwardly a greater 60 distance than either of the other sections for compressing the incandescent coke above it to the greater degree required from its weight to produce an adhesion of its particles sufficient for sustaining the greater 65 weight of the incandescent fuel in its ele-

vated position until the grate section has moved to its normal position and the intervening space is filled either with fresh or substantially fresh fuel, as may be.

On the other hand the thickness, and 70 therefore the weight of the incandescent coke directly over and above the upper grate section 27 being of less gravity requires accordingly less compression for sustaining it in its elevated position following the receding 75 of that section therefrom to its normal position.

Now, the successively increasing angular movement of the grate sections not only provides means for lifting the incandescent 80 fuel above the grate surface, and producing by compression its adhesion sufficient to sustain such fuel in its elevated position, but a means by which it is both possible and practical to introduce a uniform thickness of 85 fresh fuel between the incandescent coke and the grate surface if not a thickness increasing from the top to the bottom edges of the grate bars, and a body of coal sufficiently large to substantially increase the rapidity 90 of combustion of coal in a furnace, cooling the grate bars below the temperature at which they are liable to burn, and provide for the free and unobstructed passage of air upwardly through the grate bars, and its 95 uniform distribution throughout the products of combustion rising from fresh fuel and passing thence upwardly through a thick bed of incandescent coke.

In operation for shaking out the ashes 100 from an incandescent bed of coke resting on the surface of the grate sections in their normal position, the hand lever 40 may be rapidly reciprocated back and forth without stopping, but preferably with somewhat 105 short strokes until the ashes have sifted through, following which the strokes may be increased in length for crushing cinders lodged between the opposing ends of the grate sections, whereupon the length of the 110 movement of the lever is increased until the grate bars have reached the limit of their upward movement, and the cleansed coke from compression adheres sufficiently for sustaining it in its elevated position, until 115 coal has filled the space between its underside and the surface of the opposing grate bar.

There is substantially no limit to the thickness of the coal that may be distributed 120 uniformly between the grate surface and the incandescent coke as will be apparent when bearing in mind that the frictional resistance of the grate bar surface to the descending coal is so little that following repeated upper movements of the grate sections, the incandescent coke is lifted higher and higher with increasing thicknesses of 125 fresh fuel on the grate bars, with the result that when the grate bars are lowered the 130

fresh fuel resting on their surface will be accordingly loose, and so much of it as is in contact with the grate bars will descend with considerable rapidity thereon.

5 In conclusion it is here noted that the drawing shows (see Fig. 1) a gate 48, which may form the bottom wall of a coal chute mounted upon a pivoting rod or shaft 49 above its center of length, that is to say its 10 center of gravity, for conducting coal from a suitable source downwardly upon and in a plane with the surface of the grate bars, and which is adapted to cut off the supply of fuel to the furnace when desired for the purpose of shaking the furnace down before introducing fresh supply of coal thereto as hereinbefore described.

Having described my invention, what I claim and desire to secure by Letters Patent is:

1. An inclined grate comprising in combination a plurality of swinging sections, means pivotally suspending each of said sections below their upper ends and above their 25 longitudinal centers, whereby their surfaces move by gravity to and are thereby normally maintained in the same plane.

2. An inclined grate comprising in combination a plurality of swinging sections, 30 pivoted supports therefor, the pivots for which are located well toward but removed from their upper ends and outwardly beyond their center of gravity, and means for simultaneously swinging said sections, whereby 35 there is imparted to them an angular movement, varying with the surface of each section, producing a bed of fuel increasing in depth toward the bottom surface.

3. A furnace grate comprising in combination a plurality of swinging sections, the 40 surfaces of which are normally in the same inclined plane extending downwardly into the furnace, bearings therefor above their centers and below their upper ends, the axis 45 of which is longitudinally through each section outwardly beyond the normal center of gravity thereof, and means adapted to simultaneously produce an angular movement successively varying with each section, 50 whereby a bed of furnace fuel increasing in depth from the top to the bottom of the grate surface upon which it rests may be lifted, and thereby subjected to a compression increasing in force with the depth 55 thereof.

4. A furnace grate comprising in combination a plurality of inclined swinging sections, bearings suspending said sections respectively on longitudinal axes therethrough 60 outwardly beyond and above their center of

gravity above their longitudinal centers, a movable bar, pivots connecting said sections and bar in a plane below said bearings, the distance between which pivots and bearings substantially decreases beginning with the 65 top section.

5. A furnace grate comprising in combination a plurality of sections, side bars therefor, provided with bearings pivotally suspending each of said sections off its center of gravity, a movable bar to which said sections are pivoted at intervals thereof, a rotatable shaft for actuating said sections, means connecting said shaft with the movable bar, U-shaped brackets detachably secured to and depending from said side bars, the closed end of which furnishes a bearing supporting the shaft in a plane substantially below the side bars for the grate, and means for operating said shaft for swinging the 80 grate sections in stepped arrangement upwardly above their normal position.

6. An automatic side feed furnace comprising in combination clinker bars, sectional grates, fixed bars supported at their 85 opposite ends from the bridge and front wall of the furnace providing a common support for the lower end of the grates and the ends of the clinker bars adjacent thereto, angle irons detachably supporting the 90 upper ends of the grates, bearings for each of said several grate sections, the axis of which extends longitudinally therethrough toward their upper sides, and outwardly from the center of gravity of said sections, 95 movable bars pivotally connected at intervals of their length with the sections for each grate, a link pivoted to said bar, a rotating shaft, a crank arm thereon pivoted to said link, a hand lever for actuating said shaft, 100 and a detachable U-shaped hanger, the end wall of which slot supports and forms a bearing for the rotatable shaft.

7. A furnace grate comprising in combination a plurality of swinging sections, bearings therefor toward and below their upper ends pivotally suspending said sections off their center of gravity normally in the same plane, and means for simultaneously imparting to each of said sections an angular movement varying with each section and increasingly with each section progressively from the front to the rear of the furnace.

In witness whereof, I have hereunto set my hand and affixed my seal, this 10th day 115 of July, A. D. 1915.

JOHN H. STRUVE. [L.S.]
